UNITED STATES PATENT OFFICE.

VIRGINIA S. BENJAMIN, OF WASHINGTON, DISTRICT OF COLUMBIA, ASSIGNOR OF ONE-HALF TO CLARA L. HILL, OF THE DISTRICT OF COLUMBIA.

DESIGN FOR A PLAQUE.

Application filed November 21, 1922. Serial No. 4,356. Term of patent 14 years.

To all whom it may concern:

Be it known that I, VIRGINIA S. BENJAMIN, a citizen of the United States, and a resident of the city of Washington, District of Columbia, have invented a new, original, and ornamental Design for a Plaque, of which the following is a specification, reference being had to the accompanying drawing, forming a part thereof.

The figure is a perspective view of a plaque illustrating my new design.

I claim:—

The ornamental design for a plaque substantially as shown.

This specification signed this 18th day of November, 1922.

VIRGINIA S. BENJAMIN.
